CRANK THROW GRINDING DEVICE

John P. Morris, La Grange, Ill.

Application December 24, 1937, Serial No. 181,650

7 Claims. (CL. 51—241)

My invention relates to a device for grinding device is secured to the part of the crank shaft throw or connecting rod receiving portion 12 which needs no truing by means of the semi-cylindrical cap member 13 adapted to fit about the opposite side of the crank shaft throw 12; 5 the member 13 being secured to the main frame portion by means of suitable stud bolts and nuts as at 14. The inner circumference of the socket in the frame and the bearing cap is of somewhat greater diameter than the diameter of the throw 10 of the crank shaft to permit the insertion of suitable bearing elements 15, see Figures 1 and 2.

The invention has for its object the provision of a device whereby the connecting rod receiving portions of the crank shaft may be ground and trued without necessitating the removal of the crank shaft from the engine and therefore without necessitating a more or less complete dismantling of the engine as has heretofore been necessary; and as a result of my invention the 15 grinding or truing of these portions of the crank shaft may be accomplished with a considerable saving of time and expense.

The objects of my invention and the advantages inherent in the construction will all be 20 readily comprehended from the detailed description of the accompanying drawings, wherein:

Figure 1 is a vertical sectional view transversely of a V-shape engine with the heads of the cylinders, the pistons with the piston rods 25 and the liners removed and illustrating the application of my device to the crank shaft.

Figure 2 is a side elevation of my improved device with an intermediate portion broken away and other portions shown in section and the device shown applied to one throw of a crank shaft of which only a portion is shown.

Figure 3 is a perspective view of the lower or grinding portion of the device.

Figure 4 is a detail sectional view of the lower 35 end of the device, with the grinding wheel and its arbor omitted, so as to illustrate construction and method of mounting the arbor carrying bracket or block.

In the particular exemplification of the invention a suitable frame element 10 is employed 40 for mounting a grinding tool or wheel adjacent one end. The grinding wheel holding end of the frame is adapted to rest on and be secured about the crank-throw or connecting rod bearing of the crank shaft of the engine, namely the bearing to which two piston connecting rods are secured; while the other end of the frame 10 supports a suitable electric motor or power-imparting mechanism. The frame 10 is somewhat 45 longer than the depth of the cylinders of the engine and the lower end of this elongated frame 10 may be in simulation of a connecting rod provided at its lower end with a semi-circular socket 11 adapted to receive the connecting rod bearing 12 of the crank shaft. The frame of the 50

5 The lower socketed end of the frame 10 is of width less than the length of the connecting rod receiving bearing or throw portion 13 of the 15 crank shaft, see Figures 2 and 3, to permit the grinding element or wheel to engage the uncovered portion of the connecting rod bearing or throw of the crank shaft and for that reason the bearing cap 13 at one side is shown provided 2 with a semi-cylindrical extension 16, see Figures 2 and 3, adapted to extend about the lower side of the crank shaft throw portion to be trued. In other words, the width of the bearing cap 13 with its semi-cylindrical extension 16 approximates 25 the length of the connecting rod bearing of the crank shaft between the crank arms 11, 11 in order to maintain the device with its grinding element in position for operation on the exposed portion of the connecting rod bearing or 30 crank shaft throw and to induce a truing of one-half of the throw in keeping with the half or portion encircled by the frame and bearing cap, as shown in Figure 2.

Secured to the main frame 10 is a bracket or 35 block 18 which is provided with a spindle 19 on which an abrasive wheel 20 is loosely mounted. The bracket 18 on its opposite side is provided with a pair of stud bolts 21, 21 spaced apart and on opposite sides of the spindle-carrying axis 40 of bracket 18; and these bolts pass through the frame 10 and have their outer ends provided with suitable nuts and washers as at 22 in Figure 2. One of the openings in the frame for the passage of one of the stud bolts 21 is in the nature of a 45 vertically disposed arcuate slot which permits the bracket 18 with its spindle 19 to be vertically adjusted and positioned relative to the connecting rod bearing to be operated on.

The bore in abrasive wheel 20 is sufficiently 50 large to receive the threaded end of a combined arbor and pulley member 23 which is loosely mounted on spindle 19 to permit member 23 to rotate and to also move lengthwise of the spindle 19. The outer face of the abrasive or grinding 55

wheel 20 is countersunk about the bore in the wheel to receive nut 24 which screws onto the threaded end of the arbor and pulley member 23 as shown in Figure 2, thereby causing the wheel 20 to rotate and move with the arbor member 23. The inner end of arbor member 23 is enlarged and circumferentially grooved in the nature of a pulley 25 and is also provided with another groove 26; the pulley groove 25 being adapted to receive a suitable belt 27, while the groove 26 is adapted to receive the bifurcated end of the yoke or control member 28.

The adjusted position of the bracket or spindle carrying block 18 is controlled by a suitable cap screw 29 which is threaded through an extension or bracket arm 30 disposed laterally from the main frame 10, see Figure 1.

The yoke or control member 28 at its upper end is provided with a tapped hole adapted to receive a feed-screw 31 which is rotatably mounted on a spindle 32 provided intermediate of its ends with a collar 33; the short end of the spindle 32 extends through a hole in the main frame 10 and this end of the spindle is threaded to receive a nut 34, which causes the collar of the spindle to be firmly drawn against the side of the main frame 10.

The feed-screw 31 at its inner end is enlarged and circumferentially grooved in the nature of a pulley, as shown at 35 in Figure 2, to receive a suitable belt 36; while the outer end of the spindle 32 may be provided with a hole to receive a suitable pin to hold the feed-screw 31 against longitudinal movement on the spindle.

The belt 36 is disposed upwardly about an enlarged grooved portion or pulley 37 secured to a spindle 38 that extends loosely through the main frame 10 and is provided with a hand-wheel 39 whereby rotation of the spindle and its pulley 37 may be accomplished. The spindle 38 is shown provided with a spacing collar 40 between the hand-wheel and the frame in order to maintain the belt holding end 37 in proper vertical alignment with the enlarged grooved end 35 of the feed-screw 31.

As is apparent, the turning of hand-wheel 39 will cause belt 36 to rotate the feed-screw 31 and induce the yoke or control member 28 to travel lengthwise of the feed-screw. This movement of the control member 28 will cause the arbor 23 with the attached grinding wheel 20 to move lengthwise of the spindle 19 and consequently present the grinding wheel to different parts, namely to the entire half, of the connecting rod bearing or throw which is to be trued.

The upper end of the main frame 10 is provided with a suitable electric motor, indicated at 41, whose shaft is shown provided with a stepped pulley 42 which receives the belt 27 whereby power is imparted to the grinding wheel carrying arbor 23.

The main frame 10 at a suitable point in proximity to the path of the grinding wheel 20 is provided with a tool holding post 43, extending parallel with the grinding wheel holding arbor and the spindle 19 on which the arbor is mounted. The post 43 is provided with an opening extending transversely therethrough adapted to receive a suitable diamond point tool 44 for dressing the grinding wheel 20, held in place by a set-screw 45 which screws into a tapped hole in the end of the post and arranged to intersect the tool receiving hole in the post. The method of holding the dresser tool enables easy introduction and removal of the tool.

When dressing of the grinding wheel becomes necessary, proper rotation of hand-wheel 39 will induce the desired rotation of feed-screw 31, causing control member 28 to travel toward the main frame and simultaneously shift arbor 23 with the grinding wheel 20 lengthwise of spindle 19, where the perimeter or grinding surface of the grinding wheel will be in contact with the dresser tool 44. During rotation of the grinding wheel, it is also caused to move back and forth along the spindle 19, through proper rotation of the hand-wheel 39, thereby presenting the entire perimeter of the grinding wheel 20 to the action of the dresser tool; this operation being continued until the perimeter of the grinding wheel runs true; a resetting of the diamond point dresser being necessary during the dressing operation.

My improved device is especially intended for truing or grinding the connecting rod bearings of the crank shaft of a Diesel locomotive using the V-type Winton engines and is designed to perform this operation, provided one-half of the bearing or throw is true, without the necessity of completely dismantling the Diesel locomotive and without pulling out the crank-shaft which entails a great expense and the loss of considerable time.

In practice, the connecting or piston rods connected to the same throw or rod bearing of the crank shaft, of which one-half or part needs to be ground, are removed, as well as the bushings or liners of the cylinders and the bottom pan or cover of the crank case. My improved device is then inserted through the upper end of the cylinder with the lower semi-circular end in engagement with the true half or end of the crank shaft throw or connecting rod bearing 12, and the abrasive tool or grinding wheel 20 adjusted (by means of screw 29) to properly contact the uncovered and untrue end of the connecting rod bearing 12 of the crank shaft. The other semi-circular member or cap bearing 13 is then placed about the lower side of the connecting rod bearing 12 and fastened in place by bolts 14, with the extended portion of this cap bearing 13 disposed beneath the part to be operated on to act as a spacer and maintain the device on the true portion or end of the crank-shaft bearing or throw 12.

The frame 10 of the device, as previously stated, preferably consists of a single elongated narrow member of length somewhat greater than the distance from the top of the cylinder to the crank shaft bearing 13 when the latter is at the lowest point in its revolution, in order that the upper motor holding end as well as the hand wheel 39, of the mechanism for controlling the grinding wheel holding arbor, will be disposed above the upper end of the cylinder during the entire grinding operation.

In order that the device may be maintained in proper position and out of contact with the cylinder wall, I prefer to place a cross bar 46 across the top of the cylinder; the cross bar at opposite ends being provided with openings therethrough so that it may be inserted over some of the stud bolts 47 of the cylinder and be held in place as shown to the left in Figure 1. In locomotives of the type mentioned, the crank shaft of the Diesel engine is operatively connected with a suitable electric generator. This operative connection is left undisturbed during the use of my device in grinding crank shaft bearings. The device having been applied as described, the electric motor 44 at the top of the frame is then

energized so that it will properly drive belt 27 and thereby rotate the grinding wheel at a predetermined speed; and at the same time the generator (not shown) which is operatively connected with the crank shaft of the Diesel engine is also motorized so as to turn the crank shaft of the Diesel engine to revolve at a sufficient speed. My improved device being connected with the connecting rod bearing of the crank shaft will 10 reciprocate in the cylinder with the grinding wheel 20 in grinding relation with the crank shaft bearing during rotation and as a result the entire circumference of one end or half of the crank shaft bearing will be presented to the action of the grinding wheel. In order that the entire uncovered end of the crank shaft bearing may be acted upon, the operator will turn hand wheel 39 thereby causing rotation of the set screw 31 which induces yoke member 28 to travel 15 lengthwise of the feed screw and the yoke in turn induces the arbor with the grinding wheel to be shifted lengthwise of spindle 19. If the abrasive wheel requires dressing, a diamond point dresser tool 44 inserted in the holder 43 will contact the abrasive wheel when the latter is made to travel lengthwise of the spindle during its rotation; the dressing operation continuing until the grinding face of the abrasive wheel runs true.

If the opposite end of the crank shaft bearing 20 from that shown in Figure 2 is to be ground true, it will be understood that the device is reversed from the position shown in Figure 2. If both ends of the bearing have become untrue, the entire crank shaft will then have to be re-placed.

I have described my device as especially applicable for use in grinding the throws or connecting rod portions of the crank shaft of a Diesel locomotive, particularly of the Winton V-type engine, but it will be understood that the device is equally applicable for use in connection with any V-type engine or multi-cylinder motor whether it be of the Diesel, gasoline or other type; and the invention has been shown in what is believed to be its best embodiment and has been described in terms employed merely as terms of description and not as terms of limitation, as structural modifications may be made without, however, departing from the spirit of my invention.

What I claim is:

1. A device of the character described comprising an elongated narrow frame adapted to be inserted in the cylinder of a V-type engine and to extend from the crank shaft to the exterior of the top of the cylinder, while the lower end of the frame terminates in a semi-circular portion adapted to engage the piston-rod bearing of the crank shaft; a semi-circular bearing adapted to match the opposite side of the piston-rod bearing of the crank-shaft and to removably secure to the semi-circular portion of said frame, said bearing cap extending beyond the side of the frame coextensive with the length of the piston-rod bearing of the crank shaft; power means arranged at the upper end of said frame; a grinding wheel holding arbor rotatably mounted on the frame so as to be disposed above and in spaced relation with the extended end of said bearing cap; said arbor being also adapted to move in a direction parallel with said bearing cap; means intermediate of the power means and said arbor whereby the arbor and grinding wheel may be rotated; and means mounted on said frame and having operative connection with

said arbor whereby the arbor with the associated grinding wheel may be made to travel laterally while being rotated.

2. A device of the character described comprising an elongated frame adapted to be inserted through the cylinder of an internal combustion engine, the lower end of the frame being provided with a crank shaft bearing encircling portion the lower part whereof is provided with a lateral extension whereby the frame is held 10 against lateral movement; a grinding wheel rotatably and adjustably mounted on a horizontally disposed arbor at the lower end of the frame adjacent said bearing encircling portion and above said lateral extension; means whereby said 15 wheel is caused to travel laterally and power means disposed at the upper end of the frame and operatively connected with the grinding wheel whereby the latter is rotated.

3. A device of the character described comprising an elongated frame adapted to be inserted through the cylinder of a multi-cylinder engine, the lower end terminating in a crank shaft throw engaging portion adapted to be applied on the true end of the crank shaft throw; a frame positioning and bearing cap adapted to fit about the opposite side of the bearing and coextensive with the length of the crank shaft throw so as to extend beyond the side of the frame to maintain the latter on the true end of the throw; a vertically disposed grinding wheel rotatably mounted on the frame above the extended end of said bearing cap; grinding wheel arbor carrying means adjustably secured to said frame whereby the grinding wheel may be adjusted in a vertical direction; and power means disposed at the upper end of the frame and operatively connected with the grinding wheel arbor whereby the latter may be rotated.

4. A device of the character described comprising an elongated frame adapted to be inserted through the top of the cylinder of a multi-cylinder engine, the lower end thereof being provided with a crank-shaft throw encircling and frame positioning portion; a vertically adjustable 45 spindle carrying block secured to the frame above said encircling portion, said block being provided with a laterally disposed spindle; a vertically disposed grinding wheel rotatably and slidably mounted on the spindle; and power means disposed at the upper end of the frame and operatively connected with the grinding wheel for rotating the latter.

5. A device of the character described comprising an elongated frame adapted to be inserted 55 in the cylinder of an internal combustion engine, the lower end thereof being provided with a crank-shaft throw encircling portion; a spindle secured to the frame; a grinding wheel rotatably and slidably mounted on the spindle; means, 60 operative from the upper end of the frame, whereby movement of the grinding wheel lengthwise of the spindle may be controlled; and power means arranged at the upper end of the frame and operatively connected with the grinding 65 wheel whereby the latter may be rotated.

6. A device of the character described comprising an elongated frame adapted to be inserted in the cylinder of an internal combustion engine, the lower end thereof being provided with 70 a crank shaft encircling portion; a spindle carrying block adjustably secured to the frame; a grinding wheel carrying arbor rotatably and slidably mounted on said spindle; a feed-screw secured to the frame and adapted to be rotated; 75

- 5 a control member threaded on the feed-screw and having controlling connection with said arbor whereby rotation of the feed-screw causes said member to travel lengthwise of the feed-
screw and the arbor to travel lengthwise of said spindle; means whereby said feed-screw may be rotated; and power means arranged at the upper end of the frame and operatively connected with said arbor whereby the latter may be rotated.
10 7. A device of the character described comprising an elongated frame adapted to be inserted in the cylinder of an internal combustion engine, the lower end of the frame terminating in a semi-circular crank shaft engaging portion; a
15 bearing cap adapted to fit about the opposite side of the crank shaft and to be removably secured

to the lower end of the frame, said bearing cap being adapted to extend beyond the side of the crank shaft engaging portion of the frame; a spindle carrying block adjustably secured to the side of the frame with the spindle disposed laterally substantially parallel with the extended portion of the bearing cap; a grinding wheel carrying arbor rotatably and slidably mounted on said spindle; means operable from the upper end of the frame whereby said arbor with the grinding wheel may be moved axially; and an electric motor arranged at the upper end of the frame and operatively connected with said arbor whereby the latter and the grinding wheel may be rotated.

- 5 a control member threaded on the feed-screw and having controlling connection with said arbor whereby rotation of the feed-screw causes said member to travel lengthwise of the feed-
screw and the arbor to travel lengthwise of said spindle; means whereby said feed-screw may be rotated; and power means arranged at the upper end of the frame and operatively connected with said arbor whereby the latter may be rotated.
10 7. A device of the character described comprising an elongated frame adapted to be inserted in the cylinder of an internal combustion engine, the lower end of the frame terminating in a semi-circular crank shaft engaging portion; a
15 bearing cap adapted to fit about the opposite side of the crank shaft and to be removably secured

to the lower end of the frame, said bearing cap being adapted to extend beyond the side of the crank shaft engaging portion of the frame; a spindle carrying block adjustably secured to the side of the frame with the spindle disposed laterally substantially parallel with the extended portion of the bearing cap; a grinding wheel carrying arbor rotatably and slidably mounted on said spindle; means operable from the upper end of the frame whereby said arbor with the grinding wheel may be moved axially; and an electric motor arranged at the upper end of the frame and operatively connected with said arbor whereby the latter and the grinding wheel may be rotated.
